Primary Examiner — Messina L Smith*Assistant Examiner* — Carolyn W Davis(74) *Attorney, Agent, or Firm* — Taylor Duma LLP(57) **CLAIM**

The ornamental design for a fluted valve bonnet, as shown and described.

DESCRIPTION

FIG. 1 is a perspective view of a fluted valve bonnet according to our new design.

FIG. 2 is a left-side side elevation view thereof.

FIG. 3 is a right-side elevation view thereof.

FIG. 4 is a rear side elevation view thereof.

FIG. 5 is a front side elevation view thereof; and,

FIG. 6 is a top plan view thereof.

The broken lines illustrate portions of the fluted valve bonnet and form no part of the claimed design.

1 Claim, 6 Drawing Sheets(56)
